JUG HANDLE

David Asch, Stratford Road, Hampstead, Quebec, Canada,
and Robert D. Asch, 32 Crestwood Road, Montreal
West, Quebec, Canada

Filed May 10, 1968, Ser. No. 11,885

Claims priority, application Canada Nov. 10, 1967

Term of patent 14 years

Int. Cl. D9—99

U.S. Cl. D9—291

The broken line showing of a portion of a jug in FIGURES 1, 2 and 3 is for illustrative purposes only.

We claim:

The ornamental design for a jug handle, as shown and described.
